UNITED STATES PATENT OFFICE.

GEORGE S. WETTRICH, OF HIGHLAND PARK, AND EDWARD E. AMMON, OF DETROIT,
MICHIGAN.

SPRING-RETAINER.

1,218,730.

Specification of Letters Patent. Patented Mar. 13, 1917.

Application filed May 5, 1916. Serial No. 95,715.

To all whom it may concern:

Be it known that we, GEORGE S. WETTRICH and EDWARD E. AMMON, citizens of the United States of America, residing respectively, at Highland Park and Detroit, in the county of Wayne and State of Michigan, have invented certain new and useful Improvements in Spring-Retainers, of which the following is a specification, reference 10 being had therein to the accompanying drawings.

In the use of compression and retractile springs encircling or sleeved on valve rods, stems and plungers, we have found that 15 coiled springs tend to exert an unequal pressure around the valve rods, the pressure at one side of a valve rod being greater than at another side, consequently there is side thrust which tends to practically loosen a 20 valve rod in its guide and cause an uneven seating of a valve carried by the rod.

This, in the course of time, is very pronounced in connection with puppet valves of explosive engines, and in order to allow the 25 coiled spring to adjust itself and exert a uniform pressure around the valve rod, we have devised a novel spring retainer serving as a pressure equalizer and preventing any 30 spring pressure or action other than in the direction of the longitudinal axis of a valve rod.

The spring retainer is a simple, durable and inexpensive pressed steel proposition that can be installed in the usual manner and 35 as showing a preferred embodiment of our invention, reference will now be had to the drawing, wherein—

Figure 1 is a sectional view of a portion of an explosive engine having a puppet valve 40 held in a closed position by a spring engaging a retainer in accordance with our invention;

Fig. 2 is a plan of a detached spring retainer;

Fig. 3 is a cross sectional view taken on the line III—III of Fig. 2, and

Fig. 4 is a similar view taken on the line IV—IV of Fig. 2.

The spring retainer comprises an inverted 50 cup shaped washer 1 having a central opening 2 and an inwardly projecting flange 3 around said opening. At diametrically opposed sides of the opening 2, the top of the washer 1 is provided with depressions 4 constituting rocker sockets to receive the

ends of a transverse pin 5 carried by a valve rod 6 having a valve 7. The valve rod 6 is reciprocable in a guide 8 and the valve 7 is normally held in engagement with a valve seat 9 by the expansive force of the coiled 60 spring 10 encircling the valve rod 6 beneath the washer 1. The rocker sockets or depressions 4 are formed by cutting or stamping the body of the washer, and said rocker sockets afford a large bearing surface for the 65 transverse pin 5. Besides the valve rod 6 preventing lateral displacement of the washer, the ends of the pin 5 may abut the ends of the sockets or depressions 4 and it is impossible for the pin to become accidentally 70 displaced when the washer is held in engagement therewith. This is an important feature of our invention, irrespective of whether the washer is located below the pin or above the same.

Diametrically opposed outer edges of the washer 1 are provided with depressions 11 constituting rocker or fulcrum bosses for the uppermost convolution of the spring 10, and said bosses are disposed in a line at a right 80 angle to the depressions 4, whereby the washer will have a tilting action relative to the valve rod 6 at right angles to a tilting action of the upper end of the spring relative to the washer 1. There is consequently a universal articulation of the spring relative to the valve rod and said spring can adjust itself and distribute its expansive force so as wholly to affect the valve rod 6 in the direction of its longitudinal axis. The guide 8 of the valve rod 6 is therefore not subjected to any side thrust by said rod and the valve 7 can evenly and uniformly engage the seat 9, prevent leakage through said valve seat, and other 90 effects incident thereto.

What we claim is:

1. As a new article of manufacture, a spring retainer having rocker sockets and fulcrum bosses with the rocker socket disposed in a plane at right angles to the plane of the fulcrum bosses.

2. As a new article of manufacture, a spring retainer having diametrically opposed rocker sockets and diametrically opposed fulcrum bosses with the fulcrum bosses disposed in a plane at right angles to the plane of a rocker socket.

3. A spring retainer having a central opening, said washer having one face there- 110

of provided with rocker sockets at opposed edges of the opening of said washer, and fulcrum bosses projecting from the other face of said washer at the outer edges there-
5 of and disposed in a plane at right angles to the plane of the rocker sockets of said washer.

4. A spring retainer comprising a cup shaped washer having a central opening, the
10 outer face of said washer having opposed rocker sockets therein, and fulcrum bosses in

said washer in opposed relation and in a plane at a right angle to the plane of the rocker sockets of said washer.

In testimony whereof we affix our signa- 15
tures in presence of two witnesses.

GEORGE S. WETTRICH.
EDWARD E. AMMON.
